UNITED STATES PATENT OFFICE

GEORGE G. OBERFELL AND ALBERT M. BALLARD, OF TULSA, OKLAHOMA.

GAS-TESTING APPARATUS.

1,395,201.

Specification of Letters Patent. Patented Oct. 25, 1921.

Application filed April 27, 1920. Serial No. 377,029.

To all whom it may concern:

Be it known that we, GEORGE G. OBERFELL and ALBERT M. BALLARD, citizens of the United States, residing at Tulsa, in the county of Tulsa and State of Oklahoma, have invented certain new and useful Improvements in Gas-Testing Apparatus; and we do hereby declare the following to be a full, clear, and exact description of the invention, such as will enable others skilled in the art to which it appertains to make and use the same.

This invention relates to improvements in the methods and apparatus for testing gaseous mixtures.

A knowledge of the static and dynamic pressure of the gas and the density of the gas is required in determining the flow of gas from gas wells or from oil wells. The apparatus herein described was developed for use in connection with such tests and tests of similar nature.

Since a knowledge of the density of natural gas affords a rough idea of the gasolene content and heating value of the gas, the apparatus may be used for such purposes preliminary to testing the gas by an accurate method of analysis.

The object of the present invention is to provide improved methods and apparatus for the above purpose and to furnish an apparatus that is more compact and portable, more readily and economically constructed and operated, and is less fragile than any other apparatus known.

With the foregoing object outlined and with other objects in view, which will appear as the description proceeds, the invention consists in the novel methods and apparatus hereafter described in connection with the accompanying drawings, and more particularly pointed out in the appended claims.

Referring to the drawings:

Fig. 1 is a front view of the apparatus with the front door in open position.

Fig. 2 is a vertical sectional view taken on line 2-2 of Fig. 1. In this view the front door is closed and certain of the parts are removed.

Fig. 3 is a rear view of the apparatus with the rear door opened.

Fig. 4 is a top plan view of the apparatus casing.

55 In the drawings 1 represents the casing

which has a bottom 2, side walls 3 and 4, a top cover 7, a front door 5 and a rear door 6.

Extending across the interior of the casing is a partition plate 8 having angular edge portions 9 which are secured to the bottom and side walls and hold the bottom and side walls together. A stay bar 10 extends across the upper portion of the casing and its ends 11 are also secured to the side walls.

The top cover 7 is hinged at 12 to the side wall 3 and in normal position its free edge rests on a flange 13 provided at the upper end of the side wall 4. The doors 5 and 6 have angular edges 14 which overlap and frictionally engage the bottom, side walls and cover when the casing is closed and function to retain the cover 7 and the doors in closed position.

The partition 8 is provided with upper and lower brackets 15 which support a plurality of U-shaped glass tubes or manometers 16 and 17. The manometer 17 is filled to the desired height with a body of 80 mercury 19 and the manometer 16 contains a body 18 of light liquid, such as mineral oil, alcohol or water. The liquid bodies coöperate with suitable scales 20 and 21.

Secured to the leg 22 of the manometer 85 16 is a hollow metal fitting 23, which places the interior of the leg in communication with the interior of a pipe 24. A similar fitting 25 is connected to the leg 26 of the manometer 17 and places the interior of this 90 leg in communication with the pipe 24. Needle valves 27 and 28 are provided for closing the passages 29 and 30, which extend from said pipe.

The legs 31 and 32 of the manometers are 95 provided with removable plugs 33 and 34 which normally function to hold the liquid bodies in the manometers.

The pipe 24 has three vertically extending members 35, 36 and 37, two of which form 100 casings for the needle valves and the other of which is hollow and provided with an end closure 38 having an aperture 39. These members project through apertures in the plate 10, and nuts 40 secure the same in 105 place. A screw cover or cap 41 functions to close the aperture 39.

A branch 42 extends rearwardly from the pipe 24 and an L-shaped tube 43 is connected to said branch and carries a three-way fit- 110

ting 44. One of the legs of this fitting is connected by tubing 45 to an air pump 46. The other leg of said fitting is connected by tubing 45' to a flexible gas container 47.

5 The ends of the pipe 24 are closed by plugs 48, which may be removed when it is desired to clean the interior of said pipe.

The pump 46 in the present instance is shown as a rubber hand blower and this 10 blower is used for compressing gas from about atmospheric pressure, or pressure somewhat less than atmospheric, to several pounds above atmospheric.

The gas container 47 is preferably an 15 elastic bag and it is used as a reservoir for gas or air. The bag is preferably formed of rubber protected by a casing of some durable pliable material, such as leather. The casing prevents sudden changes of temperature 20 of the gas within the bag during tests.

To determine the specific gravity of density of a gas or gaseous mixture with the present apparatus, the method stated herein-after is carried out.

25 The valve 27 is closed, the plugs 33, 34 and the cap 41 are removed and the valve 28 is opened. The aperture 39 is then closed by the finger of the operator.

The pump 46 is then operated to force air 30 into the bag 47. As the air pressure in the bag increases, the liquid in the leg 32 of the manometer 17, rises until the desired pressure is indicated on the scale 21. A pinch clamp 49 on the tubing 45 is then closed, 35 and the finger of the operator is quickly removed from the aperture 39. The escape of air through said aperture causes a drop in pressure within the bag and this pressure drop is indicated by the fall of the mercury 40 column in the manometer 17. After the pressure has dropped to a point where it is not great enough to force the liquid from the manometer 16, the valve 27 is opened. The pressure drop is then readily observed 45 by watching the fall of liquid in the manometer 16.

The time required for any definite decrease in pressure of gas within the bag is taken by means of a stop watch. This is 50 done by starting the watch as the meniscus of the mercury 19 passes a fixed point on the scale 21 and stopping the watch as the meniscus of the light liquid 18 passes any fixed point on the scale 20.

55 The bag 47 is then purged of air. This may be done by forcing gas whose density is desired into the bag and then allowing the gas to escape therefrom. By repeating this process a few times, the bag will be free 60 from air. The bag may also be purged by connecting the suction end of the hand blower to the apparatus, closing aperture 39 and putting a reduced pressure on the bag. The bag is then filled with gas whose density 65 is desired, by means of the pump 46 or by

attaching the tubing 45 to a suitable connection on the gas supply providing said gas supply exists under sufficient pressure. The time is then again noted in like units for a pressure drop equal to that used with air. 70 The specific gravity is calculated as follows:

$$\text{Specific gravity} = \frac{(\text{gas time})}{(\text{air time})}$$

For example if it were determined that 75 the time for pressure drop of gas was 80 seconds and that the time for pressure drop of air was 100 seconds, the specific gravity, or density, of the gas would be, therefore, 0.64.

The combination of a mercury gage and a light liquid gage permits of the reading of a wide range of pressure with a small height for the manometer, and makes possible a sensitive method for timing pressure drop. 80

The flow of the gas may be determined by means of the orifice meter or Pitot tube by methods readily understood by those skilled in the art. The manometers 16 and 17 may be used for noting the pressure as is required in such tests. 90

We are aware that several changes may be made in the design, construction and operation of an apparatus such as we have described without departing from the spirit of 95 this invention. For example, the apparatus may be successfully used with one manometer. The time required for any definite decrease in pressure of gas within the bag is determined by timing the pressure drop by 100 the fixed limits on the scale of the one manometer only. The apparatus may also be so constructed as to feed most of the gas through the orifice under a constant pressure. We have found that apparatus having such modifications do not give results of 105 greater accuracy, and are more difficult to operate. 110

What we claim and desire to secure by Letters Patent is:—

1. A method of testing a gaseous mixture to determine the specific gravity of said mixture, which method consists of forcing air and gas alternately into a chamber, placing the air and gas alternately under pressure, allowing the gas or air in the chamber to escape through an orifice, indicating the decreases in pressure within the chamber as the gas or air escapes, noting the time required for dissipation of said gas or air 115 pressure between desired pressure limits, and calculating the specific gravity from the relation between the times required for dissipation of gaseous mixture pressure and dissipation of air mixture pressure through the 120 same pressure limits.

2. In a method of determining the specific gravity of a gaseous mixture, the steps of alternately placing air or the gaseous mixture in containing means, compressing the 130

- air or gaseous mixture to a predetermined degree, permitting the air or gaseous mixture to escape from the containing means through an aperture to reduce the pressure 5 by the same amount for both the air and gas, and noting the difference in time required to permit the exit of the air or gaseous mixture through the aperture to reduce the pressure within the containing means.
- 10 3. In a method of determining the specific gravity of a gaseous mixture, the steps of placing air in a containing means, compressing the air to a desired degree, permitting the air to escape from the containing means 15 through an aperture, timing the period required for permitting the pressure of the air to fall a desired degree, placing a compressed gaseous mixture in said containing means and permitting the escape of said 20 gaseous mixture through said aperture, noting the time required for pressure of the gaseous mixture to drop equal to the pressure drop of the air, and calculating the density or gravity of the gaseous mixture from the 25 periods of time required for the pressure drops.
4. A gas testing apparatus including a container for gas or air, a plurality of manometers communicating with said container, one of said manometers containing a 30 heavier liquid than the other manometer, for forcing air under pressure into said container, and means for closing the communication between the container and either of 35 said manometers, and means for permitting the exit of air or gas from said container.
5. An apparatus as defined in claim 4 in which the communication closing means includes a manually controlled valve.
6. A gas testing apparatus comprising a 40 pipe, a plurality of manometers connected to said pipe and normally communicating with the interior of the same, means for closing communication between the pipe and manometers, a two branched tube extending 45 from said pipe, a container for air or gas having its interior communicating with one branch of said tube, an air pump connected to the other branch of said tube, and means providing a restricted orifice for permitting 50 the escape of air or gas from said container.
7. An apparatus as defined by claim 6 in which the liquid of one manometer is heavier than the liquid of the other manometer.
8. A gas testing apparatus comprising a 55 casing having front and rear doors, a partition dividing the interior of the casing into a plurality of compartments, a pipe, a plurality of manometers connected to said pipe and located in one of said compartments, a 60 container for air or gas and an air pump located in the other compartment, means connecting the container and pump to the pipe, and means for permitting the exit of air or gas from said container.
9. An apparatus as defined in claim 8 in which means are provided for closing communication between the manometers and pipe.

In testimony whereof we affix our signatures.

GEORGE G. OBERFELL.
ALBERT M. BALLARD.
